(57) **CLAIM**

The ornamental design for a handbag, as shown and described.

DESCRIPTION

FIG. 1 is a top perspective view of a handbag;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a partial enlarged view of the handbag taken from dash-dot-dash broken line circle “9” in FIG. 1; and,

FIG. 10 is a partial enlarged view of the handbag taken from the dash-dot-dash broken line circle “10” in FIG. 2.

The evenly dashed broken lines depict portions of the handbag and form no part of the claim. The dash-dot-dash broken lines represent the boundaries of the partial enlarged views and form no part of the claim.
